Robert Thaler INVENTOR

BY

Geo. B. Willcox ATTORNEY

UNITED STATES PATENT OFFICE.

ROBERT THALER, OF WEST BAY CITY, MICHIGAN.

SCREW-PROPELLER.

SPECIFICATION forming part of Letters Patent No. 698,584, dated April 29, 1902.

Application filed January 20, 1902. Serial No. 90,515. (No model.)

To all whom it may concern:

Be it known that I, ROBERT THALER, a subject of the Emperor of Germany, residing at West Bay City, in the county of Bay and State 5 of Michigan, have invented certain new and useful Improvements in Screw-Propellers; and I do hereby declare the following to be a full, clear, and exact description of the invention, such as will enable others skilled in the 10 art to which it appertains to make and use the same.

This invention relates to an improvement in screw-propellers, the object of the invention being to provide a simple and efficient 15 propeller having large area of blade-surface and large area of bearing-surface upon the projecting portion of the stern-post to prevent the shaft being bent or broken when the blade strikes an obstruction.

20 Another object is to provide means for automatically removing dirt and grit from the rubbing-surfaces of the propeller and the projection on which it turns.

With this object in view the invention consists in certain novel features of construction and combinations and arrangements of parts, as hereinafter set forth, and pointed out in the 25 claim.

In the accompanying drawings, Figure 1 is 30 a perspective view of the propeller and shaft. Fig. 2 is a part-longitudinal section of the propeller in place on the projecting bearing of the stern-post. Fig. 3 is an enlarged section taken on the line $x-x$ of Fig. 1.

35 A represents the screw, the length of which is preferably somewhat greater than the diameter. The blades are helical in form and in revolving describe a cylinder of uniform diameter. The shaft 1 is rigidly secured, by 40 means of the key 2, to the outer end of the hub and fits the bore of the hub tightly from its outer end to about its middle. The other end of the hub is provided with a conical recess 3, extending axially from the forward 45 end of the screw and tapering to its smaller end 3^a about midway the length of the screw.

The inner surface of the conical recess is finished to form a smooth bearing-surface.

The stern-post of the vessel is fitted with a 50 rearwardly-projecting boss 4, which carries at its outer end a conical bearing 4^a, the outer surface of which exactly fits and forms a

bearing for the inner surface 3 of the revolving hub. The shaft 1 extends axially through the projection 4 and the conical bearing 4^a. 55

In order to remove dirt or other foreign substances from between the rubbing-surfaces of the hub and the conical bearing 4^a, I provide through the shell of the hub pairs of slits 5, separated by intermediate bars 5^a, 60 through which the dirt can escape. In practice I prefer to shape the intermediate bar 5^a as shown in Fig. 3, having inner scraping edges 5^b, which mechanically remove the dirt from the surface of the bearing 4^a and discharge it into the water through openings 5. 65

In practice I prefer to arrange a sufficient number of slits 5 around the hub and to make them of such length that the paths of succeeding slits as they travel around the conical bearing will overlap, thus thoroughly 70 cleaning every part of the rubbing-surface.

By constructing the hub of the screw-propeller as above described and mounting it upon the conical bearing 4^a, which is rigidly 75 attached to the stern-post of the vessel, I produce a screw having great lateral rigidity and one which cannot be easily broken by striking snags or other obstacles.

What I claim as my invention, and desire 80 to secure by Letters Patent, is—

A propeller for vessels comprising in combination a series of helical blades of greater length than the diameter of the propeller; a hub integral with said blades; an axial hole 85 through said hub, the outer portion of the length of said hole being adapted to fit the propeller-shaft; the remaining portion of said hole being enlarged from the middle of the hub toward its forward end, to form a conical 90 recess; openings through the conical shell of the hub; and scraping-bars across said openings; together with a conical rearwardly-extending bearing secured to the vessel and fitting the conical recess of the hub, said bearing having an axial shaft-opening, all arranged substantially as and for the purposes set forth.

In testimony whereof I affix my signature in presence of two witnesses.

ROBERT THALER.

Witnesses:

I. GOULD,

JAMES C. HANSON.
